CLAIM

The ornamental design for a connector of an anal irrigation system, as shown and described.

DESCRIPTION

FIG. 1 is a perspective view of a connector of an anal irrigation system, where the connector is provided with a reservoir component and is attachable to a section of replacement tubing;

FIG. 2 is a front elevation view of the connector illustrated in FIG. 1;

FIG. 3 is a back elevation view of the connector illustrated in FIG. 1;

FIG. 4 is a left side elevation view of the connector illustrated in FIG. 1;

FIG. 5 is a right side elevation view of the connector illustrated in FIG. 1;

FIG. 6 is a top plan view of the connector illustrated in FIG. 1;

FIG. 7 is a bottom plan view of the connector illustrated in FIG. 1; and,

FIG. 8 is a perspective view of the connector of the anal irrigation system, with the connector secured to the reservoir component by tubing and attached to the section of replacement tubing.

In FIGS. 1–6 the broken lines illustrate a tubing port on a top end of the connector and form no part of the claimed design. In FIG. 8 the broken lines illustrate tubing secured between the reservoir component and the connector and the section of replacement tubing connected to the connector, where the tubing and the reservoir component and the section of replacement tubing form no part of the claimed design.
